UNITED STATES PATENT OFFICE.

CHESTER J. WERNER, OF CLEVELAND, OHIO.

PISTOL-SWORD.

1,284,843.

Specification of Letters Patent. Patented Nov. 12, 1918.

Application filed July 18, 1918. Serial No. 245,537.

To all whom it may concern:

Be it known that I, CHESTER J. WERNER, a citizen of Russia, residing at Cleveland, in the county of Cuyahoga and State of 5 Ohio, have invented certain new and useful Improvements in Pistol-Swords, of which the following is a specification.

The primary object of the invention is the provision of a combined pistol and sword, 10 employing substantially the usual form of automatic pistol which is detachable from the sword portion of the device when desired, although the pistol may be readily reloaded and fired when the device is assembled and during which time the sword may 15 also be freely used.

A further object of the invention is to provide a sword adapted for readily housing an automatic pistol in locked relations 20 with respect thereto so that the pistol as well as the blade of the sword may be freely used either separately or simultaneously.

A still further object of the invention is the provision of a combined sword and pistol 25 in a single weapon which is light in weight and inexpensive to manufacture.

The device will now be fully described in connection with the accompanying drawings in which like reference characters designate 30 corresponding parts throughout the several views, and in which—

Figure 1 is a side elevation of the device assembled.

Fig. 2 is an enlarged transverse sectional view thereof taken upon line II—II of Fig. 4 with the clamping member illustrated by dotted lines in its released position.

Fig. 3 is a similar sectional view taken upon line III—III of Fig. 4.

Fig. 4 is a side elevation of the device 40 with parts broken away.

Fig. 5 is a top plan view thereof, and

Fig. 6 is a bottom plan view thereof.

My device consists of a sword having a 45 blade 10 projecting from a grip portion 11 which together with a hand guard 12 carried by said grip constitutes a form of hilt for the sword. An opening or slot 13 is formed in the grip 11 at the side thereof 50 opposite the guard 12 with an opening 14 extending through said grip permitting the passing of the stock 15 of an automatic pistol through the opening 14 for seating a por-

tion of the barrel 16 and the adjacent part of the pistol within the slot 13. 55

Opposite ribs 17 are provided upon the pistol adapted for sliding in opposite grooves 18 formed in the opposite walls of the slot 13, while the trigger 19 of the pistol is provided rearwardly of the stock 15 adjacent a forward curved portion 20 of the hand guard 12 readily accessible by the finger of the hand when grasping the sword grip 11.

A plurality of screws 21 are preferably 65 employed for securing the hand guard 12 to the pistol grip 15. A yoke 22 is carried by one end of the grip 11 adjacent its point of attachment with the blade 10 and clamping jaws 23 are hinged to the opposite ends 70 of said yoke as at 24. The said jaws are provided with suitable sockets 25 upon their inner faces for grasping the pistol barrel 16 and a bolt 26 having a winged nut 27 is carried by the free end portions 28 of the 75 clamping jaws for retaining the jaws upon the barrel when the device is assembled. Perforations 29 are also provided in the jaw ends 28 for convenience in attaching the device to any desired support. 80

It will be understood that when the device is assembled, the hinged plate 30 at the free end of the stock 15 of the pistol may be opened when it is desired to reload the pistol with cartridges 31. Automatic means 85 are provided within the stock 15 for taking up waste space therein consisting of plates 32 hinged together as at 33 and to the cover plate 30 at 34. Coöperating springs 35 are provided upon the plates 32 90 and 30 for normally pressing one of the plates 32 against the adjacent cartridge 31 tending to force the cartridges within the stock 15 toward the barrel 16 of the pistol. 95

It will be understood that the grip 11 may be readily grasped for wielding the sword in using the blade 10 thereof, while at the same time the trigger 19 may be pulled for firing the pistol whenever desired. Upon releasing the bolt 26 and removing the 100 screws 21, the entire pistol may be readily detached from the sword which leaves the sword slot complete and ready for use while the pistol may be easily reinserted in its assembled relations with the sword whenever desired. A combined weapon is pro- 105

vided possessing great strength and utility without materially adding to the weight of an ordinary sword and pistol.

What I claim as new is:

- 5 1. A device of the class described comprising a sword having a grip provided with a groove in one side thereof and a transverse opening communicating therewith adapted for the seating reception of an automatic pistol, a hand guard upon the grip adapted for attachment to the stock of the pistol when the device is assembled, a blade extending from said grip, a yoke secured to the grip adjacent its point of attachment with said blade and retaining jaws hinged to the opposite ends of said yoke adapted for encircling the barrel of a pistol for locking the pistol to the grip.
- 10 2. In combination with a sword hilt having an opening therethrough, an automatic pistol removably secured within the said opening, a blade carried by the hilt, clamping jaws hingedly connected to the hilt surrounding the barrel of said pistol and locking means connecting the said jaws.
- 15 3. A pistol sword including a sword grip, a pistol transversely positioned therethrough having its stock projecting laterally from the grip and providing a cartridge magazine, a hinged closure plate for said magazine, hingedly connected spacing plates within the magazine hinged to said closure

plate, springs carried by and engaging adjacently positioned ones of said plates adapted for resilient engagement with the cartridges within the magazine.

4. In combination with a sword grip having an opening therethrough provided with side grooves, a pistol positionable through said opening with its stock projecting from said grip and having opposite ribs slidably positioned within the said grooves, a hand guard upon said grip and screws connecting the said guard to the stock of the pistol.

5. In combination with a sword grip having an opening therethrough provided with side grooves, a pistol positionable through said opening with its stock projecting from said grip and having opposite ribs slidably positioned within the said grooves, a hand guard upon said grip, screws connecting the said guard to the stock of the pistol, a yoke carried by the grip adjacent the rear end of the blade of the sword, jaws hinged to the opposite ends of said yoke having recessed inner faces clampingly engaging the barrel of the pistol when the device is assembled and provided with alining openings adjacent their free ends, a bolt connection between said jaws and a retaining nut upon the said bolt.

In testimony whereof I affix my signature.

CHESTER J. WERNER.
